CLAIM

The ornamental design for a RF transmitter module, as shown and described.

DESCRIPTION

FIG. 1 is a front elevational view of the RF transmitter module of the present invention;

FIG. 2 is a back elevational view of the RF transmitter module of the present invention;

FIG. 3 is a side elevational view of the RF transmitter module of the present invention, the other side thereof being a mirror image; and

FIG. 4 is a top plan view of the RF transmitter module of the present invention; and,

FIG. 5 is a bottom plan view of the RF transmitter module of the present invention.
